DESIGN FOR A SUBMARINE

Sam T. Rogers, Washington, D. C.

Application June 13, 1938, Serial No. 77,814

Term of patent 14 years

To all whom it may concern:

Be it known that I, Sam T. Rogers, a citizen of the United States, residing at Washington, in the District of Columbia, have invented a new, original, and ornamental Design for a Submarine, of which the following is a specification, reference being had to the accompanying drawings, forming part thereof.

Fig. 1 is a side elevational view of a submarine, showing my new design.

Fig. 2 is a bottom plan view.

Fig. 3 is a top plan view.

Fig. 4 is a front elevation.

Fig. 5 is a rear elevation.

I claim:

The ornamental design for a submarine, as shown.

SAM T. ROGERS.
